UNITED STATES PATENT OFFICE.

WILLIAM D. HOXIE, OF NEW YORK, N. Y., ASSIGNOR TO THE BABCOCK & WILCOX COMPANY, OF BAYONNE, NEW JERSEY, A CORPORATION OF NEW JERSEY.

WATER-TUBE BOILER.

1,102,407.

Specification of Letters Patent. Patented July 7, 1914.

Application filed January 12, 1912. Serial No. 870,750.

To all whom it may concern:

Be it known that I, WILLIAM D. HOXIE, a citizen of the United States, residing in New York city, borough of Brooklyn, county of 5 Kings, and State of New York, have invented certain new and useful Improvements in Water-Tube Boilers, of which the following is a specification.

My invention relates to a water tube boiler 10 and will be understood by reference to the following description taken in connection with the accompanying drawings in which—

Figure 1 is a view in part elevation and in part transverse section, of a boiler embodying the invention; Fig. 2 a central longitudinal section of Fig. 1; Fig. 3 a transverse section to illustrate a modification in which the boxes into which the generating tubes are expanded extend transversely instead of 20 longitudinally of the banks of tubes; Fig. 4 a view of a portion of two of the boxes of Fig. 3 with the hand hole covers removed; Fig. 5 a transverse section of another modification; and Fig. 6 is a side view of a portion of Fig. 5 looking in the direction of the arrow.

Similar reference numerals indicate similar parts in the several views.

Several of the features hereinafter described are applicable to a boiler of a single unit and I wish to be understood as not limiting myself to a boiler comprising two units disposed relative to each other as shown in the drawings, unless it is specifically so claimed.

As shown in Figs. 1 and 2, the boiler comprises two units, 1 and 2 symmetrically disposed with reference to the central longitudinal plane of the setting, each unit comprising a bank of inclined water tubes, the 40 banks being inclined so as to converge toward each other upwardly to provide a relatively large A-shaped combustion chamber 3 between them. The boiler may be fired with oil, burners 4 being shown for that purpose. The method of firing is, however, not material, as the boiler may be set over a coal fired furnace. The tubes of both banks are expanded at their upper ends into 45 a central longitudinal steam and water drum 5, and at their lower ends into water

boxes 6 of relatively small transverse section, the tubes being preferably staggered to prevent lanes and to cause the products of combustion to be broken up in their passage 55 across the tube surfaces. The water boxes 6 are placed at right angles to the axes of the tubes at their lower ends and when adjacent to each other form practically a continuous water wall and tube sheet. They may extend either longitudinally or transversely of the setting, the former arrangement being shown in Figs. 1 and 2, with two longitudinal rows of tubes to a box. In the wall opposite the tube ends are hand holes 7 through 60 which access to the box may be had for expanding the tube ends. Also at one or both ends of each box 6 is a hand hole 8 through which the entire interior of the corresponding box may be inspected. At either or both ends of the water boxes 6 is a transverse box 9 of approximately the same section as the boxes 6 and connected to the latter by tubes or nipples. These transverse boxes 9 act as blow-off collectors through which the boiler 70 may be entirely drained, or may serve to supply additional water for circulation. The side walls 10 are built up to the lower row 75 of tubes 11 of each bank to protect the undersides of the lowermost boxes 6; and the side walls 12 extend from the uppermost box 6 to the uptakes, the boxes 6 being supported at their ends on brackets or saddles on the plates 13 at the front and rear of the setting. The hand hole sides of the boxes 80 are therefore readily accessible, the boxes running lengthwise or crosswise of the boiler 85 at a convenient height above the floor line.

In some designs of water tube boilers having inclined generating tubes, the lower ends of the tubes are expanded into water drums. These drums are of small diameter and it is an exceedingly difficult matter to expand the lower ends of the tubes into the tube sheet, and when necessary to renew a tube 95 sheet the cost is large as the entire bank of tubes is destroyed. The present design, employing a plurality of boxes 6, presents a distinct advantage in that a defective box can be replaced at small expense, it being 100 only necessary to renew the generating tubes expanded into that box. Any work to be

done on the lower tube ends can be performed by the operator in the ample space provided at the sides of the boiler outside of the walls 10, and the work can be much more effectively done than if the workmen were compelled to squeeze into a small water drum where the space is greatly confined or a drum so small as to prevent access altogether. Also by the use of boxes all riveted joints are eliminated in the pressure parts located at the lower parts of the boiler. At the extreme end of each longitudinal box 6 I provide tubes 14 to act as a down-comer or water supply to the lower boxes.

15 As shown in the drawings, the generating tubes are perfectly straight for their entire length except at their upper ends where they are curved for a short distance in order that they may enter the steam and water drum 5 radially. An advantage incident to such form of tube is that the entire interior of the tubes can be seen when examined from both ends and also thoroughly cleaned when necessary. Transverse baffles 15 and 16 can be readily placed in the banks, the former across the uptake ends of the tubes, and the latter approximately midway between the baffle 15 and the boxes 6. In addition to these baffles I provide a longitudinal baffle 17 among the lower tubes of each bank, said baffles extending from the boxes 6 upwardly to the first pass, thus forming the inclined sides of the A-shaped combustion chamber which chamber is open to the gases or products of combustion only along the upper parts of its sides, that is at the upper ends of the tubes. Supported on the outside row of tubes of each bank is a baffle 18 extending from the steam and water drum 5 downwardly to the cross baffle 16. By the system of baffles employed separate portions of the gases are caused to travel across and around the tubes, as indicated by the arrows, to the separate outlet flues 19 and 20. It will be noted that the boxes 6 above the baffles 17 are exposed only to the heat of the escaping gases, their life being thereby prolonged. If desired, the longitudinal baffle 17 may be supported on the lowermost row of tubes and extend from the side walls 10 to the first pass, thus putting all of the boxes in the coolest part of the boiler, in which case the cross baffle 15 would extend from the lowermost row of tubes of the two banks.

In Figs. 3 and 4 I have shown a modification in which the lower ends of the generating tubes are expanded into boxes 21 extending transversely of the bank instead of longitudinally as shown in Figs. 1 and 2. These transverse boxes may be in the form of headers corrugated so as to stagger the tubes for the same purpose that they have been described as staggered in connection

with Fig. 1. All the advantages incident to accessibility by placing the hand hole sides of the boxes 21 outside of the side walls of the setting apply as in the case of the longitudinal boxes. A blow-off connection 22 is nipped to the lower ends of boxes 21.

In Figs. 5 and 6 I have shown another modification in which the lowermost box 21 in Fig. 3 is replaced by a box 23 extending longitudinally of the boiler and transverse of the boxes 21, and connected by pipes 75 or nipples 24 to the lower ends of all of the boxes 21. In this form the longitudinal baffles 17 are supported on the row of tubes expanded into each of the boxes 23.

What I claim and desire to secure by Letters Patent of the United States, is:

1. A water tube boiler comprising a bank of inclined water tubes, a steam and water drum into which the upper ends of said tubes are expanded, boxes into which the lower ends of the tubes are expanded in groups or rows, said tubes being curved at their upper ends and straight for the rest of their length, and a blow-off collector box connected to the boxes into which the tube ends are expanded.

2. A water tube boiler comprising two units each consisting of a bank of water tubes inclined toward each other upwardly to form between them an A-shaped combustion chamber, a central steam and water drum into which the upper ends of the tubes of both banks are expanded, and a plurality of boxes into which the lower ends of the tubes are expanded in groups or rows, said tubes being curved at their upper ends and straight for the rest of their length, and a blow-off collector box connected to the boxes into which the tube ends are expanded.

3. A water tube boiler comprising two units each consisting of a bank of water tubes inclined toward each other upwardly to form between them an A-shaped combustion chamber, a central steam and water drum into which the upper ends of the tubes of both banks are expanded, a plurality of boxes into which the lower ends of the tubes are expanded in groups or rows, downcomers connecting the water space of said drum with said boxes, and a blow-off collector box connected to the boxes into which the tube ends are expanded.

4. In a water tube boiler comprising two units each consisting of a bank of water tubes inclined toward each other upwardly to form between them an A-shaped combustion chamber, a central steam and water drum into which the upper ends of the tubes of both banks are expanded, a plurality of boxes into which the lower ends of the tubes are expanded, in groups or rows, said tubes being curved at their upper ends and straight for the rest of their length, trans-

verse baffles dividing each bank into a plurality of passes and longitudinal baffles extending from said boxes to the first pass and from the steam and water drum to the last 5 pass, and a blow-off collector box connected to the boxes into which the tube ends are expanded.

In testimony whereof I have hereunto signed my name in the presence of two subscribing witnesses.

WILLIAM D. HOXIE.
